HANDBAG

Leon E. Meadow, New York, N. Y.

Application March 3, 1951, Serial No. 213,764

5 Claims. (Cl. 150—28)

1

The present invention relates to a lady's handbag and is generally directed to the provision of a lady's handbag which is of new, highly novel and attractive construction and appearance.

It is an object of the present invention to provide a lady's handbag in which a rigid frame is provided on the exterior with the pocket or bag portion disposed on the interior of the frame.

It is another object of the present invention to provide a lady's handbag of the character described in which the frame is provided with a closure which is likewise on the exterior of the bag and which is operated by the handles of the bag.

It is a further object of the present invention to provide a lady's handbag of the character described which is spacious and which, besides being highly attractive in appearance, is also easy and convenient to open and to close and comfortable to carry.

It is a still further object of the present invention to provide a lady's handbag of the character described which is economical to produce and is sturdy and durable.

The foregoing and other advantages and superiorities of the lady's handbag of the present invention will become more readily apparent to those skilled in the art from the embodiment thereof shown in the accompanying drawing and from the description following. It is to be understood, however, that such embodiment is shown by way of illustration only, to make the principles and practice of the invention more readily comprehensible and without any intent of limiting the invention to the specific details therein shown.

In the drawings:

Fig. 1 is a fragmentary, top plan view of the lady's handbag of the present invention shown in open position, and partly cut away to show structural details;

Fig. 2 is a top plan view of the lady's handbag shown in closed position;

Fig. 3 is an elevational view of the lady's handbag shown in partly open position; and

Fig. 4 is a bottom plan view of the handbag frame.

Referring more specifically to the accompanying drawing, the lady's handbag of the present invention comprises an outer frame consisting of an open-work or cage-like receptacle portion, generally designated as 10, which may be of substantially any desired shape, such as the bucket shape shown, and is formed of relatively thin pieces of material, such as the wire illustrated, or thin narrow metal or plastic slats. The receptacle frame section 10 may comprise the annularly disposed, upright, evenly spaced wires,

2

11, which may be connected to one another by annular ribs at their tops and bottoms, as at 12 and 13, soldered or otherwise secured, preferably on the exterior faces of the wires 11, and additional intermediate ribs, such as 14.

The bottom, 15, of the frame section 10 may also be of open-work, if desired, formed of horizontal, spaced wires or the like, 17, which may be integrally continuous with the wires 11.

10 The handbag frame also includes an open-work closure formed by a plurality of approximately U-shaped closure elements, 20, of wire or similar material, all preferably of the same size, which are secured by the ends of their legs, 21,

15 as by loops, 22, formed thereon to the upper annular rib 12 of the receptacle frame section 10. The closure elements 20 are arranged in overlapping position, each element having one leg 21 overlying the contiguous leg 21 of an adjacent element 20 at one side and underlying

20 the contiguous leg 21 of an adjacent element 20 at the other side, so that when any one of the elements 20 is moved inwardly or outwardly it will actuate, serially, similar movement of all of the other closure elements.

25 The frame of the handbag of the present invention is further provided with a pair of handles that may also serve for actuating the closure elements of the frame. Such handles may each comprise an approximately U-shaped member,

30 generally designated as 25, having a pair of leg portions, 26, and a web portion, 27, with the section of the U member immediately adjacent the web portion being preferably widened and offset outwardly from the leg portions, as at 28, the web 27 serving as a handle grip.

35 Each of the handles 25 is secured to the upper rib 12 of the receptacle frame section 10, as by loops, 29, formed on the ends of their legs 26 which fit about such rib. One of the legs 26 of

40 each of the handle members 25 is disposed above or outwardly of the closure elements 20 and the other being disposed below or inwardly thereof, so that each of the legs 26 of each handle 25 may serve to actuate such elements 20 in one direction, either towards opening or closing, so that when the two handles are moved apart the closure elements 20 are moved into opening position and when the two handles 25 are pushed together the closure elements 20 are moved into closing position.

45 The handbag of the present invention is also provided with a bag portion, generally designated as 30, which may, if desired, be seamlessly formed of a square of textile or textile substitute fabric, 31, preferably of ornamental design which will be decoratively visible through the open-work frame. The fabric square 31 may be in-

50 55

serted into the frame section 10 with its center resting on the bottom 15 of the frame section 10, and its corners, 32, projecting above the frame section 10. The fabric square 31 may be secured within the handbag as by means of an annular row of spaced rings, 33, secured, as by sewing, in proper position on its outer face, which rings 33 engage over the upper rib 12 of the frame section 10.

It will be readily apparent that the corners 32 of the fabric square 31 will fold over the pocket or bag 30 formed by the main body portion of such square to serve as a closure or cover therefor and as protection for its contents; it being, obviously, quite easy to move such corners in and out of covering position.

This completes the description of the handbag of the present invention. It will be readily apparent that such handbag is highly effective for its purpose as a receptacle for the articles generally carried by a lady in a handbag; that it is light of weight; that it is of strong and sturdy construction; that it is easy and convenient to use; and that it is of simple construction, formed of relatively low priced material by relatively simple and economical processes and is therefore economical to produce.

It will be further apparent that numerous variations and modifications may be made in the handbag of the present invention particularly as to the shape and form of its several frame sections and the form and material of the elements from which such frame sections are formed, which variations and modifications may be made by anyone skilled in the art in accordance with the principles of the invention hereinabove set forth and without the use of any inventive ingenuity. I desire, therefore, to be protected for any and all such variations and modifications that may be made within the spirit of the present invention and the scope of the claims hereto appended.

What I claim is:

1. A lady's handbag comprising an open-work receptacle frame section having side walls formed of a plurality of rigid, relatively narrow, spaced upright elements secured to horizontal ribs including a rib at the upper end of said elements, closure elements each comprising a substantially U-shaped member having leg portions pivotally secured by loops formed at their ends to said upper rib, said closure elements secured to said rib in overlapping position relative to one another whereby movement of one of said elements will actuate the other of said elements for similar movement, a pair of handle elements each comprising a U-shaped member having spaced leg portions pivotally secured to said upper rib by loops formed at the ends of the leg portions thereof, one of said leg portions overlying said closure elements and one of said leg portions underlying said closure elements whereby movement of the handle in any direction will actuate said closure elements for movement in a similar direction.

2. A lady's handbag comprising, the combination with an open-work receptacle frame section including a bottom, rigid lattice work side walls, a horizontal rib at the upper edge of the side walls and closure elements pivotally secured on said rib and arranged to interchange for simultaneous movement upon the movement of any of them, of handle means comprising a pair of handle elements, each of approximately U-shape and having spaced leg portions, each

pivotally secured by its end to said upper rib with one of said leg portions overlying said closure elements and the other of said leg portions underlying said closure elements, whereby movement of a handle in any direction will actuate said closure elements for movement in a similar direction.

3. The handbag of claim 2 wherein each of said handle elements has its free end portion outwardly offset to form a grip section which will extend in approximately upright direction when its inner end portion is in approximately horizontal handbag closing position.

4. A lady's handbag comprising, in combination, an open-work receptacle frame section including a bottom, rigid lattice work side walls, a horizontal rib at the upper edge of the side walls and closure elements pivotally secured on said rib and arranged to interengage for simultaneous movement upon movement of any of them and handle means comprising a pair of handle elements, each of approximately U-shape and having spaced leg portions each pivotally secured by its end to said upper rib, with one of said leg portions overlying said closure elements and the other of said leg portions underlying said closure elements, whereby movement of a handle in any direction will actuate said closure elements for movement in a similar direction, and a pouch within said frame section, said pouch comprising a substantially rectangular textile fabric section disposed in cupped arrangement within said frame section and secured to said horizontal rib along points arranged approximately circularly over the central portion thereof, whereby the marginal portions of said fabric section are detached from said frame section and free to form a cover for the pouch formed thereby.

5. A lady's handbag comprising, in combination, an open-work receptacle frame section, open at its top and having a bottom, rigid lattice work side walls, a horizontal rib at the upper edge of the side walls and closure elements pivotally secured on said rib and arranged to interengage for simultaneous movement upon movement of any of them, and handle means secured to said frame section adjacent the opening thereof, and a pouch within said frame section, said pouch comprising a flat textile fabric section of greater dimensions than the opening of said frame section disposed in cupped arrangement within said frame section and secured to said horizontal rib along points arranged circularly over the central portion thereof on a circumference greater than the opening of said frame section, whereby the central portion of said fabric section forms a receptacle portion and the marginal portions thereof are detached from said frame section and free to form a cover for the pouch formed from the said fabric section.
